UNITED STATES PATENT OFFICE.

ALBERT LE. EBVRE, OF PRE SAINT GERVAIS, FRANCE.

OIL PUMP.

Application filed January 6, 1925. Serial No. 891.

To all whom it may concern:

Be it known that I, ALBERT LEFEBVRE, a citizen of the Republic of France, and residing at Pre Saint Gervais, Seine Department, 5 No. 5 Rue Deltal, in the Republic of France, have invented certain new and useful Improvements in Oil Pumps, of which the following is a specification.

The present invention relates to an improved oil pump provided with means affording a rapid priming and a practical regulation of the output, while at the same time the inspection and cleaning of the pump will be much facilitated.

10 The said pump is chiefly adapted for the supply of lubricators of the sight-feed type, and in this event the apparatus comprises a plurality of pumps operating upon a common oil tank, but the device according to the invention is obviously applicable to oil pumps of all types, irrespectively of their use and of the number of delivery conduits.

15 The appended drawing shows by way of example two constructional forms of the device according to the said invention.

Fig. 1 shows one constructional form of the device.

Figs. 2 and 3 are modifications.

As shown in Fig. 1, the said pump comprises a cylinder 1 co-operating with the piston 2 to which is secured a screwthreaded socket or hollow screw 3 engaged in a nut 4 which is mounted upon an eccentric strap or frame 5; the said piston comprises an extension or tongue 6 engaging by easy friction in a corresponding slot 7 of a second piston 8, or priming piston, so that the two pistons are connected together as concerns their rotation.

20 The piston 8 is provided with a controlling knob 9 by which it may be rotated together with the piston 2 in order to screw or unscrew the latter with reference to the nut 4, or to give the piston 8 a reciprocating motion when pumping by hand, for instance for priming the pump. The strap 5 is controlled by an eccentric 10 which is mounted upon the shaft 11; when the said shaft rotates, the eccentric 10 will alternately push 25 the rear portion of the said strap in order to effect the suction, and the outer end of the piston 2 in order to effect the delivery.

25 The output of the pump is regulated by turning the knob 9 in either direction so as to rotate the piston 2 and the screw 3; this will vary the space between the rear of the

said eccentric frame and the outer end of the piston, so that the stroke of the piston can be regulated for the desired output. According as the said space is made shorter, 60 the output of the pump will be increased.

The piston 8 is preferably urged in the outward direction by a spring 12 so as not to interfere with the working of the piston 2 and to facilitate the priming operation. A 65 spacing strip 13 elastic or not, is removably mounted upon the outer end of the piston, and is thus interposed between the screw 3 and the eccentric 10; the said strip supports the wear of the eccentric and can be readily 70 replaced when out of use.

The pump withdraws from the oil tank 14 through the medium of a ball-valve 15; and the delivery takes place through the clack valve 16.

75 The modification shown in Fig. 2 differs from the first form of construction by an arrangement of seats for the clack valves whereby the removal and inspection of the said valves will be facilitated. The pump cylinder 1 is provided at the lower part with a screw cap 17 serving to maintain a socket 18 in which are formed the seats of the two valves 15 and 16; said socket is traversed by the pistons 2 and 8, but the said pistons can be laterally removed, and in this event the socket 18 can be readily removed through the bottom together with the two valves for purposes of inspection. To this end the pump cylinder 1 comprises a stuffing box 19 80 which can be dismounted with facility for the removal of the piston 8; on the other hand, the frame 5 is so constructed as to be coupled to the shaft 11, and it may pivot upon trunnions 21 which are mounted upon 85 the nut 4, so that it will suffice to lift the same in order to draw the piston 2 towards the interior of the oil tank; in this manner the pistons 2 and 8 may be disengaged from the socket 18, and after removing the cap 17 90 the said socket can be dismounted together with the valves.

95 Fig. 2 further shows a modified form of the connection between the pistons 2 and 8; the end of the piston 2 is hollow and has 105 therein the longitudinal slot 22; on the other hand the piston 8 is loosely engaged in the piston 2 and is provided with the stud 23 which is slidable in the slot 22 and serves to impart to the piston 2 the movements of rotation which are given to the piston 8 by 110 means of the knob 9.

Obviously, any other suitable connecting means may be employed, for instance a square or polygonal aperture is formed in the piston 2 whilst the piston 8 comprises a co-operating projection which is loosely slideable in the said aperture.

In Fig. 2, the spring 12 is disposed at the exterior of the cylinder 1 and in the rear of the knob 9 instead of being placed within 10 the cylinder 1 as shown in Fig. 1.

It should be noted that the adjustable connection between the piston 2 and the frame 5 of the eccentric may be inverted, i. e. a nut such as 4 may be mounted on the said 15 piston and a screw 3 upon the said frame, and this inversion will not modify the operation of the device.

The pump represented in Fig. 3 comprises also a cylinder 1, which is screwthreaded 20 at its end 24, a delivery-piston 2, an adjusting nut 4, a priming and adjusting piston 8 provided with a controlling knob 9.

The reciprocating motion of the piston 2 is produced by the cam 10 mounted on the 25 shaft 11, and the delivery is obtained by means of said cam, while the suction is produced by means of the spring 25.

The knob 9 controls, through the medium 30 of the piston 8, the piston 2 as shown on the drawing and the movement is transmitted by means of a split-pin or a square-shaped end. The end of the piston 2 is in fact formed by a square-shaped rod 26 on which the nut 4 can slide, this nut being provided with a square-shaped bore, so that 35 the parts 9, 8, 2 and 4 are secured together in the sense of rotation.

The shoulder formed by the square-shaped 40 end and the cylindrical part of the piston 2 bears against the inner part of the nut 4 in order to limit the course of the piston during the suction.

The rotation of the knob 9 will cause the 45 nut 4 to move forward and backward on the screw 24 in order to increase or to shorten the course of said piston and to increase or to decrease the delivery.

Having thus described my process and 50 apparatus, what I claim as new therein, and my own invention, is:

1. In an oil pump operated by a driving shaft, cylindrical pump body, a piston disposed therein, adjustable means for actuating the said piston by the driving shaft, a second piston coaxial with the first-mentioned piston, means for actuating the second piston by hand from the exterior of the pump, means connecting the said pistons together in such manner that they will be longitudinally slideable but not revolvable upon each other, a suction valve, a delivery valve, and seats for the said valves formed in the said pump cylinder.

2. In an oil pump operated by a driving

shaft, a cylindrical pump body, a piston disposed therein, a screw mounted upon the said piston, an eccentric strap, a cam cooperating therewith and keyed to the said driving shaft, said cam acting on one side upon the said piston and on the other side upon the side of the strap opposite the said piston, and a nut attached to the said strap and engaging the said screw, a second piston coaxial with the first-mentioned piston, means for actuating the second piston by hand from the exterior of the pump, means connecting the said pistons together in such manner that they will be longitudinally slideable but not revolvable upon each other, a suction valve, a delivery valve, and seats for the said valves formed in the pump chamber.

3. In an oil pump operated by a driving shaft, a cylindrical pump body, a piston disposed therein, a screw mounted upon the said piston, an eccentric strap, a cam cooperating therewith and keyed to the said driving shaft, said cam acting on one side upon the said piston and on the other side upon the side of the strap opposite the said piston, and a nut attached to the said strap and engaging the said screw, a second piston coaxial with the first-mentioned piston, a milled knob secured to the outer end of the second piston, the first piston having a bored-out portion and a slot, and the second piston being provided with an extension which is slideable in the said bore of the first piston, a pin being mounted upon said extension and engaging the said slot, a suction valve, a delivery valve, and seats for the said valves formed in the said pump cylinder.

4. In an oil pump operated by a driving shaft, a cylindrical pump body, a piston disposed therein, a screw mounted upon the said piston, an eccentric strap, said strap having the shape of a hook which is disposed around the driving shaft, a cam cooperating with the said strap, and keyed to the driving shaft, said cam acting on one side upon the said piston and on the other side upon the side of the strap opposite the said piston, a nut pivoted to the said strap and engaging the said screw, a second piston coaxial with the first-mentioned piston, means for actuating the second piston by hand from the outside of the pump, means connecting the said pistons together in such manner that they will be longitudinally slideable but not revolvable upon each other, a suction valve, a delivery valve, and a socket removably mounted in the said pump body, said socket comprising seats for the said valves.

In testimony that I claim the foregoing as my invention, I have signed my name.

ALBERT LEFEBVRE,
